H. T. BUSSMANN

ELECTRIC FUSE

Filed May 7, 1919

INVENTOR

HENRY T. BUSSMANN,

By *J. G. Morris* ATTORNEY.

UNITED STATES PATENT OFFICE.

HENRY T. BUSSMANN, OF ST. LOUIS, MISSOURI.

ELECTRIC FUSE.

Application filed May 7, 1919. Serial No. 295,374.

My invention relates to electric fuses and refers particularly to removable ferrule contact cartridge fuses; yet I do not limit my invention to this type as certain of my improvements are likewise desirable in other types of fuses.

The object of my invention is to provide a fuse that is easily renewed and that is not affected by the varying dimensions of fiber.

These advantages of my invention will be more readily understood by reference to the accompanying drawings, which show a preferred embodiment of my invention. In describing the device shown in the drawings, hereto attached and described in the specification, I do not limit my invention to the precise form, shape or construction of the fuse shown, or to the several parts thereof, as various alterations can be made without changing the scope of my invention.

Fig. 1 is a view of my fuse showing the longitudinal section thereof. Fig. 2 is a perspective view of the various parts of my fuse.

In the drawings, 3 is a casing, 4 is a ring-shaped member partly within the casing and which preferably is arranged so that the cap or ferrule 7 may be held thereon. This member, which is preferably made of metal or other material of unchanging dimensions, may be attached to the casing by rivets or other means, but I prefer to use threads as shown at 5. By reason of its being attached to the inside of the casing, the shrinking of the fiber more firmly grips the member. This is of great advantage over such type of fuses as have the fittings on the exterior of the casing, as the shrinking of the fiber then permits the fittings to become loose and permits the escape of flame and gas. Where the cap is directly attached to the fiber, great difficulty is experienced in removing the cap when the fiber swells. I eliminate this trouble by providing holding means, preferably threads 6, to detachably position the cap 7 on the member 4. The member 4 is held against rotation by means of the rivet 8.

The fuse strip 10 is bent down on the plug 11. Rotation of this plug is prevented by the non-circular interior 12 of the member 4. This non-circular interior also serves to

close that part of the interior of the case not covered by the plug.

To more effectively close the case and thereby guard against the difficulties experienced by the deposit of metal on the various parts of the fuse caused by the blowing of the fuse, I make the joint between the member 4 and the plug 11 so as to secure a wedging action, as such wedging action takes up the difference in thickness of various size strips that may be used and assures of the case being tightly closed at all times, effectively preventing the expulsion of metallic vapors, flame or gas. In my preferred form, I make the aperture 13 with straight sides and the plug with tapered sides on the greater portion of its periphery and while this taper may be of any length, I prefer to have it extend along the entire length of the plug. The side at which the strip is positioned is preferably at right angles to the top of the plug.

I claim as my invention:

1. In a fuse, a casing, a cap, a cap-holding member attached to the casing, having an aperture thru which a fuse link may be passed, a plug adapted to be wedgewise positioned in and to substantially close said aperture and having an outer face over which a link may be bent, and co-acting means on cap and cap-holding member adapted to press a fuse link toward the plug and the plug toward the aperture.

2. In a fuse, a casing, a cap, a cap-holding member attached to the casing, having an aperture thru which a fuse link may be passed, a plug adapted to be wedgewise positioned in and to close said aperture and co-acting means on cap and cap holding member pressing the plug in the aperture and for holding a fuse link between the cap and the plug in substantially unchanging electrical contact.

3. In a fuse, a casing, a cap, a cap holding member fitted within the casing and having a non-circular aperture, a plug adapted to be wedgewise positioned in said aperture and co-acting means on the cap and member for pressing the plug in the aperture and adapted to hold a fuse link between the cap and the plug.

HENRY T. BUSSMANN.
